(57) **CLAIM**

The ornamental design for a “magnetic wax applicator”, as shown and described.

DESCRIPTION

FIG. 1 is a perspective view of a magnetic wax applicator, showing my new design;

FIG. 2 is a left side elevational view thereof, the right side elevational view being a mirror image thereof;

FIG. 3 is a rear elevational view thereof;

FIG. 4 is a front elevational view thereof;

FIG. 5 is a top plan view thereof; and,

FIG. 6 is a bottom plan view thereof.

The broken line showing of a surface as well as the broken lines on the top of the applicator in FIG. 1 are for illustrative purposes only and Form no part of the claimed design.
